DISPENSER

Victor J. Cassano, Dayton, Ohio, assignor to Cassano Enterprises, Inc., Dayton, Ohio, a corporation of Ohio

Filed Feb. 12, 1968, Ser. No. 10,553

Term of patent 14 years

Int. Cl. D7—99

U.S. Cl. D44—22

FIG. 1

FIG. 1 is a top plan view of a dispenser, showing my new design;

FIG. 2 is a front elevational view thereof; and

FIG. 3 is a right side elevational view thereof, the side opposite being substantially the same except for the absence of the lever and slot and the presence of the handle.

The bottom is a conventional recessed rotatable slotted plate.

I claim:

The ornamental design for a dispenser, as shown and described.
